EDWIN E. GREAVES, OF SYRACUSE, NEW YORK, ASSIGNOR TO CROUSE-HINDS COMPANY,
OF SYRACUSE, NEW YORK, A CORPORATION OF NEW YORK.

FASTENER FOR BOXES.

1,287,000.

Specification of Letters Patent. Patented Dec. 10, 1918.

Application filed July 23, 1915. Serial No. 41,547.

To all whom it may concern:

Be it known that I, EDWIN E. GREAVES, a citizen of the United States, and a resident of Syracuse, in the county of Onondaga and State of New York, have invented a certain new and useful Fastener for Boxes, of which the following is a specification.

This invention has for its object a simple and efficient clamping means for securing two parts together, particularly adapted to 10 secure a cover to a box, and more especially adapted to secure the trim of a panel board cabinet to the box or cabinet; and the invention consists in the novel features of construction hereinafter set forth and claimed.

In describing this invention, reference is had to the accompanying drawings, in which like characters designate corresponding parts in all the views.

20 Figure 1 is a plan view, partly in section, of a portion of a panel board cabinet embodying my invention, the trim being removed but the position thereof being indicated in dotted lines.

25 Fig. 2 is a vertical sectional view on line A—A, Fig. 1.

Fig. 3 is an elevation of parts seen in Fig. 2.

30 Fig. 4 is an elevation of parts seen in Fig. 3 looking to the left.

1 designates the side walls of a panel board cabinet, and 2 the trim, these parts corresponding to the sides and cover of a box or cabinet, or to any two parts to be clamped 35 together.

The side walls 1 are shown as formed with inturned flanges 3 at their tops upon which rests the cover or trim 2. The clamping means is here shown as carried by the cover 40 or trim 2 and includes a jaw movable under and out from under the flange 3 about an axis and movable rectilinearly toward and from the flange, an operating part carried by the cover to move the jaw rectilinearly 45 and about an axis during one continuous operation of said part, and means for guiding the jaw during its movement.

4 designates the jaw which is in the form 50 of an elongated nut having a threaded passage nearer one end than the other, and 5 is the operating means which is a screw extending through the trim 2 and through the threaded passage of the nut 4, the screw being normally held from endwise movement 55 relatively to the cover or trim 2. The guid-

ing means by which the nut is moved by the screw rectilinearly toward and from the flange 3 and about the axis of the screw when disengaged from the flange 3 by merely turning the screw in the ordinary manner 60 without any additional manipulation, comprises a guide 6 carried by the trim 2 and having a guide-way in the form of an angular slot having a portion or arm 7 extending lengthwise of the guide 6 parallel to the 65 screw, and another portion or arm 8 extending about the axis of the screw or parallel to the thread, that is, the portion 8 is of the same incline as the thread.

The guide 6 is also formed with laterally 70 extending ears 9 which may be secured to the cover 2 in any suitable manner, as by riveting or spot welding.

A suitable shoulder 10 is provided on the nut, which shoulder extends through the 75 angular slot. As here shown, this shoulder 10 is a screw extending through the angular slot in the guide 6 and into the nut, the head thereof engaging the outer face of the guide. This guide is shown as having an inner arc-shaped face 11 concentric with the axis of the screw, and also with an arc-shaped outer face, and the nut is shown as formed with an end face 12 concentric with the screw, the face 12 engaging the face 11 of the guide- 80 way.

Said face 12 includes a cylindrical portion concentric with the screw and a conoidal portion beveled off at 13 on the upper side of said face in the direction of movement of 90 the clamp into operative position, that is, upwardly toward the upper side of the jaw or nut. When the screw is being turned to clamp, the jaw naturally stands at an incline, with the end of the jaw on which the 95 working face is located elevated above the opposite end of the jaw. The beveled portion 13 of the jaw permits the screw to stand in this manner thus avoiding binding of the jaw on the guide 6. However, when the 100 working face of the jaw engages the part to be clamped, as the flange 3, continued turning movement of the screw causes the screw to assume a vertical position, and the jaw a horizontal position and the jaw to brace 105 against the guide 6 with the cylindrical portion of its end face engaged with the inner cylindrical face 11 of the guide.

Preferably, the working face of the jaw is raised as at 14. Hence, the jaw has a bear- 110

ing on opposite sides of the screw, which feature is advantageous as the screw is offset from the working face and the force of the screw is applied to the nut at a point remote from where the nut engages the flange 3. The screw is held from endwise movement so that the turning of the screw will effect an endwise movement of the jaw or nut 4 by any suitable means, and as here shown said means is a compression spring 15 interposed between the cover or trim 2 and the nut, the spring having an arm 16 at its lower end which rests in a seat 17 in the upper face of the nut or jaw 4.

15 In operation, the clamping means is applied to the cover or trim, and the cover or trim placed in position on the flanges of the side walls of the box. By a mere turning movement of the screw, owing to the angular 20 slot, the nut or jaw 4 is first turned so that it is under the flange 3, and continued turning movement of the screw without any attention being given to the nut by the operator, moves the nut into clamping position, 25 and when it is desired to remove the cover, a simple unscrewing operation of the screw will first move the nut endwise until the shoulder 10 passes out of the lengthwise portion 7 of the angular slot and then the nut 30 will turn about its axis out from under the flange 3 owing to the transverse arm or portion 8 of the angular slot.

What I claim is:—

1. A clamp comprising a non-endwisely 35 movable screw, a jaw threading on the screw, and a guide having an angular guideway extending parallel to the screw and about the axis of the screw, the jaw having means engaging the guideway, substantially as and for the purpose specified.

2. The combination of two parts to be clamped together, and a clamp comprising a screw extending through one of said parts, a jaw into which the screw threads, movable 45 into engagement with the other of said parts, and a guide carried by the former part and formed with an angular guideway, one portion of which extends parallel to the screw and another portion of which extends in a 50 direction about the axis of the screw, the jaw having means engaging the guide, substantially as and for the purpose set forth.

3. The combination of two parts to be clamped together, and a clamp comprising a 55 screw extending through one of the parts, a jaw into which the screw threads, movable into engagement with the other of said parts, a guide carried by the former part and formed with an angular guideway, one portion of which extends parallel to the screw, and another portion extends about the axis 60 of the screw, the jaw having means engaging the guide, and a spring acting to hold the screw from endwise movement, substantially as and for the purpose described.

4. The combination of two parts to be clamped together, and a clamp comprising a screw extending through one of said parts, a nut on the screw movable thereby into engagement with the other of said parts, 70 means for holding the screw from endwise movement, and means for holding the nut from rotation during a part of the turning of the screw, and permitting the nut to turn with the screw during another part of the 75 turning movement of the screw, substantially as and for the purpose specified.

5. The combination of two parts to be clamped together, and a clamp including a screw extending through one of said parts, 80 a jaw comprising a nut threading on the screw and movable into and out of engagement with the other of said parts, and a guide carried by the former part and having an angular slot, one arm of which extends 85 parallel to the screw, and another arm of which extends about the axis of the screw, and the nut having means extending into the slot, substantially as and for the purpose set forth.

6. The combination of two parts to be clamped together, and a clamp including a screw extending through one of said parts, a jaw comprising a nut threading on the screw and movable into and out of engagement 95 with the other of said parts, a guide carried by the former part and having an angular slot, one arm of which extends parallel to the screw, and the other arm of which extends about the axis of the screw, and the 100 nut having means extending into the slot, and a spring inserted between the jaw and the opposing face of the part through which the screw extends, substantially as and for the purpose described.

7. The combination of two parts to be clamped together, and a clamp comprising a screw extending through one of said parts and being held from endwise movement, a jaw threading on the screw, and a guide 110 formed with an inner surface concentric with the screw and also with a guideway including a portion extending parallel to the screw, and a portion extending about the axis of the screw, the jaw having a face co-acting with the inner face of the guide and arranged concentric with the screw and also having a shoulder extending into the guideway, substantially as and for the purpose 115 specified.

8. The combination with a box including a side having an inturned flange, and a cover resting on the flange, of a screw extending through the cover crosswise of the edge of the flange, a nut on the screw having a portion movable under and out from under the flange and toward and from the flange, and means for holding the nut from turning movement during part of the operation of the screw and permitting the nut to turn 125 130

- with the screw during another part of the operation of the screw in the same direction, substantially as and for the purpose described.
5. A clamp comprising a jaw having a raised working face near one end, means for operating the jaw connected to the jaw between its ends, and guiding means arranged to loosely engage the jaw, the operating 10 means normally permitting the jaw to stand at an incline relatively to the guiding means and the jaw having a face arranged to engage the guide as the jaw approaches its final position to arrange the jaw at a right 15 angle to the guiding means, substantially as and for the purpose described.
10. A clamp comprising a screw, a jaw threading on the screw and having a working 20 face offset from the screw, and means for bracing the jaw and coacting with the end face thereof on the opposite side of the screw to that on which the working face is located, said means extending parallel to the screw, substantially as and for the purpose 25 specified.
11. A clamp comprising a screw, a jaw threading on the screw having a working face offset from the screw, the jaw also having a bearing face at one end thereof, said 30 working face and said bearing face being located on opposite sides of the screw, the bearing face being beveled off in the direction of movement of the jaw into clamping position, and means engaging said end face 35 of the jaw and serving to brace the jaw as the same is moved by the screw into its final clamping position, substantially as and for the purpose set forth.
12. A clamp comprising a screw, a jaw
- threading on the screw and having a working face offset from the screw and an end bearing face, the working face and the bearing face being located on opposite sides of the screw, said bearing face having a cylindrical portion concentric with the screw, 45 and a conoidal portion beveled off in the direction of movement of the jaw into clamping direction, and a guide having an inner face concentric with the screw and coacting with the bearing face on the end of the jaw, 50 the guide having an angular guideway including a portion extending parallel to the screw and a portion extending about the axis of the screw, and the jaw having means engaging the guideway, substantially as and 55 for the purpose described.
13. The combination with two parts to be clamped together, of a clamp comprising a screw extending through one of said parts, a jaw into which the screw threads movable 60 into and out of engagement with the other of said parts, the jaw having a working face offset from the screw, and a bearing face including a portion extending parallel to the screw and a portion beveled off in the 65 direction of the jaw into a clamping position, and a guide carried by the former part and coacting with the bearing face, substantially as and for the purpose specified.
- In testimony whereof, I have hereunto 70 signed my name in the presence of two attesting witnesses, at Syracuse, in the county of Onondaga, and State of New York, this 7th day of April, 1915.

EDWIN E. GREAVES.
